UNITED STATES PATENT OFFICE.

SARAH E. McCREARY, OF HIGHLAND, KANSAS.

ATTACHMENT FOR CORSETS.

1,258,028.

Specification of Letters Patent. Patented Mar. 5, 1918.

Application filed October 18, 1917. Serial No. 197,247.

To all whom it may concern:

Be it known that I, SARAH E. McCREARY, a citizen of the United States, and a resident of Highland, in the county of Doniphan and State of Kansas, have invented certain new and useful Improvements in Attachments for Corsets; and I do hereby declare the following to be a full, clear, and exact description of the invention, such as will enable others skilled in the art to which it appertains to make and use the same.

This invention relates to improvements in an improved attachment for corsets and more particularly to means for adjusting and controlling the corsets,—one object of my invention being to provide a garment supporting device attachable to the leg of the wearer and to the lower portion of the corset in such manner as to hold the corset down to proper place and prevent the same from flaring upwardly or outwardly, without discomfiture to the wearer during the various movements of the legs and body when walking or in a sitting position.

A further object is to so construct the device as to avoid possibility of cramping or pinching any part of the leg; so that it will not tend to retard proper blood circulation, and so that it will serve the double purpose of properly holding the corsets in place, preventing the same from pulling up or flaring, and also act as an efficient hose supporter.

With these and other objects in view, the invention consists in certain novel features of construction and combinations of parts as hereinafter set forth and pointed out in the claims.

In the accompanying drawings; Figure 1 is a view in side elevation, illustrating an embodiment of my invention; Fig. 2 is a front view, and Fig. 3 is a rear view.

It is to be understood that my improved garment supporting device will be used in pairs so as to be employed on both legs of the wearer, but it will suffice to illustrate and describe one device only.

In the drawing, a portion of a leg is represented at 1 and the lower portion of a corset is shown at 2.

3 represents a pad which is made in such shape as to be adaptable to the leg under or behind the knee,—the respective ends of said pad being preferably made with two edges 4—5 disposed at an obtuse angle to

each other. To the edges 4 at respective ends of the pad, the lower ends of check straps 6, are secured. These check straps may be made of elastic fabric and may be provided with adjusting means as indicated at 7 and at their upper ends, they are provided with attaching means 8 for connection to the lower edge of the corset.

Straps 9—9 are secured to the lower beveled edges 5 at respective ends of the pad 3 and are removably connected together by a suitable fastening device 10. One or both of the straps 9 may be provided with an adjusting slide 11. The straps 9, 9, and pad 3 form an anchor band for the check straps, and encircles the leg below the knee.

Straps 12—12 are secured to the respective check straps 6 at points above the knee and are removably connected by a suitable fastening device 13. One or both of these straps may be provided with a suitable adjusting slide 14.

It will be observed that the pull of the corsets will be transmitted directly to the pad 3 by the check straps 6 and that the strain thus coming upon the pad will be transmitted to the anchor band below the knee of the leg. It will also be apparent that the straps 12, which form a partial band partly encircling the leg above the knee, will hold the check or pull straps in proper position and at times, when the strain on the check or pull straps is great, the partial band formed by the straps 12 will assist in sustaining such strain.

My improvements will operate effectually to hold the corset in place and prevent it from flaring, without discomfiture to the wearer, and the hose will also be held properly in place.

Having fully described my invention what I claim as new and desire to secure by Letters-Patent, is:—

1. A device of the character described, comprising a pad adaptable for application to the leg of the wearer behind the knee, check straps secured to the end portions of said pad and adaptable for connection with the lower portion of a corset, an anchor member secured to the ends of the pad and forming therewith an anchor band to engage the leg of the wearer below the knee, and a strap connecting the check straps and adapted to partly encircle the leg above the knee.

2. A device of the character described,

comprising a pad adaptable for application to the leg of a wearer behind the knee, check straps secured to the ends of the pad and extending upwardly therefrom for attachment to a corset, anchor straps secured to the ends of the pad, means for removably connecting said anchor straps below the knee of the wearer, and removably connected straps connected with the check straps and

adapted to partly encircle the leg of the wearer above the knee.

In testimony whereof, I have signed this specification in the presence of two subscribing witnesses.

SARAH E. McCREARY.
